(57) **CLAIM**

We claim the ornamental design for mounting arm for
electronic display, as shown.

DESCRIPTION

FIG. 1 is a front perspective view of a mounting arm for
electronic display according to the invention;

FIG. 2 is a front elevation view of a mounting arm for
electronic display according to the invention;

FIG. 3 is a rear elevation view of a mounting arm for
electronic display according to the invention;

FIG. 4 is a top plan view of a mounting arm for electronic
display according to the invention;

FIG. 5 is a bottom plan view of a mounting arm for
electronic display according to the invention; and,

FIG. 6 is a side elevation view of a mounting arm for
electronic display according to the invention.
